CLAIM

I claim the ornamental design for a keychain multitool, as shown and described.

DESCRIPTION

FIG. 1 is a front perspective view of a first embodiment of a keychain multitool, according to my design;

FIG. 2 is a left side view of the keychain multitool of FIG. 1;

FIG. 3 is a right side view of the keychain multitool of FIG. 1;

FIG. 4 is a front view of the keychain multitool of FIG. 1; FIG. 5 is a rear view of the keychain multitool of FIG. 1; FIG. 6 is a top view of the keychain multitool of FIG. 1; FIG. 7 is a bottom view of the keychain multitool of FIG. 1; FIG. 8 is a front left perspective view of a second embodiment of a keychain multitool, according to my design; FIG. 9 is a left side view of the keychain multitool of FIG. 8;

FIG. 10 is a right side view of the keychain multitool of FIG. 8;

FIG. 11 is a front view of the keychain multitool of FIG. 8; FIG. 12 is a rear view of the keychain multitool of FIG. 8; FIG. 13 is a top view of the keychain multitool of FIG. 8; and,

FIG. 14 is a bottom view of the keychain multitool of FIG. 8.

The broken lines shown in the drawings illustrate portions of the keychain multitool that form no part of the claimed design.

1 Claim, 8 Drawing Sheets
